UNITED STATES PATENT OFFICE.

LOREN W. McOMBER, OF PEORIA, ILLINOIS.

DESIGN FOR A TRAFFIC LIGHT.

Application filed December 10, 1923. Serial No. 8,000. Term of patent 14 years.

To all whom it may concern:

Be it known that I, LOREN W. McOMBER, a citizen of the United States, residing at 565 Linn Street, in the city of Peoria, and county of Peoria, and State of Illinois, have invented a new, original, and ornamental Design for a Traffic Light, of which the following is a specification, reference being had to the accompanying drawing, forming part thereof.

The figure is a side view of a traffic light, showing my new design.

I claim:

The ornamental design for a traffic light, as shown.

LOREN W. McOMBER.
